CHRISTIAN A. VOLF, JR., OF WEEHAWKEN, NEW JERSEY, ASSIGNOR TO MURRAY T. QUIGG, OF NEW YORK COUNTY, NEW YORK

SOUND RESONATING AND MODULATING DEVICE

Application filed December 31, 1929. Serial No. 417,706.

This invention relates to a sound resonating and sound modulating device adapted for use in auditoriums, theaters and the like, which may be made in a form to be used particularly for ornamental purposes. The present invention is an improvement or modification of the forms of my invention described in applications Serial No. 323,019, filed December 1, 1928, Serial No. 340,926, filed February 18, 1929, and Serial No. 404, 314, filed November 2, 1929.

The preferred form of the present invention comprises sound generating means, a sounding box connected to the sound generating means, a series of resonating tubes suspended at different levels from a tube board, connected at the bottom of the sounding box and encased in a cylindrical casing of material having the characteristics of glass or bakelite, the tubes being suspended over a container adapted to hold a liquid by which the sound waves from the tubes will be vibrated, mingled, blended and discharged, and the various parts of the device being interconnected and designed to give a harmonious ornamental appearance.

Among the objects of my invention is to provide a sound resonating apparatus of the general form described and claimed in the applications referred to above, but which is modified in a manner to render it particularly adapted for use as a chandelier or other ornamental fixture, whereby sound waves may be transmitted to the auditorium or chamber in which it is used from any desired location and in any desired direction without requiring additional space and without interfering with the artistic appearance of the auditorium or chamber in which it is placed.

Various other objects of the invention will be apparent from the following description and claims.

My invention is illustrated in the accompanying drawings, showing the various features of my invention in which:

Fig. 1 is a view in perspective of a device embodying my invention;

Fig. 2 is a sectional view in elevation of the device shown in Fig. 1;

Fig. 3 is a cross-sectional view of the sound-

ing box of the device taken on the section line 3—3 of Fig. 2 in the direction of the arrows;

Fig. 4 is a plan view showing a view of the interior of the liquid container by which sound vibrations from the resonating tubes 55 are vibrated, mingled, directed and discharged into the auditorium in a predetermined path or paths;

Fig. 5 is a view in elevation, partly in section, showing the preferred arrangement for 60 mounting the resonating tubes on the pipe board;

Fig. 6 is a plan view of the form of mounting shown in Fig. 5;

Fig. 7 is a detailed sectional view in elevation showing the preferred form of supporting means between the different levels of the pipe supporting units;

Fig. 8 is a vertical sectional view of a modified form of mounting in which the various 70 tubes are supported upon square sections arranged at different levels, and

Fig. 9 is a plan of the form of support shown in Fig. 8.

Referring more particularly to the drawings, my invention comprises the sound resonating apparatus designed particularly to provide a pleasing ornamental appearance, whereby it may be used, as above stated, as a chandelier or hanging fixture to produce 80 an artistic appearance wherever it is employed.

The invention comprises preferably a sounding box 10 made of wood of sufficient thickness to give the desired strength and to 85 provide the desired resonating properties, the material employed being free from knots and other imperfections which would interfere with the sound resonating characteristics of the sounding box.

The sides of the box are preferably reinforced at the corners by means of triangular pieces or sections of wood 12 running lengthwise and transversely of the interior of the box at the junction of the side elements with the top portion and with the bottom portion thereof. Similar triangular sections or pieces are preferably employed at the junction of the sides with one another, these 95 triangular sections serving to prevent inter- 100

ference of the sound waves and to produce improved resonating qualities in the casing.

A sound generating means 14 of any suitable form may be connected to a cone or horn 16 which in turn connects with a sounding box 10 through a suitable opening 18 at the top of the sounding box. At the lower side or bottom portion of the sounding box 10 is a larger opening 20 in which is a circular tube board 22, adapted to hold a series of resonating tubes 24, the tube board being made of bakelite, or other suitable material, and having a sufficient thickness and strength to hold the weight of the tubes used. The tube board 22 may be made in sections as hereinafter described, and is preferably fastened to the bottom portion of the sounding box by means of brackets 26 attached to the interior of the sounding box. By the use of a sounding box 10 as shown, instead of a casing as a baffle board for the unit, the tubes 24 may be made of any desired length, even a 32 foot tube being adapted for this construction.

The resonating tubes are preferably held in place on the tube board by means of copper wires 28 fastened to the upper end of the tubes, thus forming a seat serving to hold the tubes suspended from the tube board in a downward position.

The resonating tubes 24 are preferably encased in a cylindrical casing 30 of suitable material adapted to give the desired artistic appearance, such as glass, bakelite, or similar moldable composition which may be transparent or opaque as desired, and may be colored or without color as may be preferred under the particular conditions of use. Obviously the cylindrical casing may be ornamented with any suitable form of design to harmonize with the general appearance of the device and the surrounding objects or decoration of the chamber or room in which it is used.

The casing should obviously be made of suitable thickness so as to prevent cracking or undue vibration of the device during use and may obviously be modified somewhat in form so as to vary proportions and dimensions as will be apparent to those skilled in the art.

The casing is preferably supported by means of a frame or ornamental support 32 which may be connected by means of chains 34 to the lower or bottom portion of the sounding box 10, the chains being preferably attached at the inside of the bottom member 36 of the frame or support. An opening 38 in the bottom of the supporting member 32 serves to permit passage of sound waves from the resonating tubes 24 to the surface of a liquid 40 in the liquid container 42. The liquid container is preferably suspended by means of chains 44 from the exterior of the bottom portion 36 of the supporting member 32.

The container 42 is preferably constructed having dimensions and form to harmonize with the sounding box 10 and the supporting member 32. This container 42 is preferably made of wood having sloping walls 46 forming an angle of about 45° with the horizontal or with the bottom 48 of the container. The inner sides of the container 42 preferably comprise the four long sides or walls 46 and four connecting pieces or short sides 50 at the corners of the container. The chains 34 and 44 connecting parts of the device are preferably in alignment, as shown more particularly in Figs. 1 and 2, the chains being preferably connected to the various parts of the device by means of rings 52. The device is also preferably suspended by chains 54 from a support 56 which in turn is supported by a chain 58 in a manner to form a harmonious appearance as shown.

In the preferred form of tube mounting as shown, particularly in Figs. 5, 6 and 7, in which the tubes are arranged at different levels, the resonating tubes of the lowest frequency 24' are preferably suspended from or supported on an uppermost support, preferably an annulus 60, and form the outermost series of tubes. The uppermost or outer tube supporting member 60 may be attached to the bottom of the sounding box 10 by means of brackets 26 in the manner indicated more particularly in Fig. 3 of the drawings. The tubes 24² responding to the notes of next higher frequency than those attached to support 60 are supported upon an annular or circular section 62 at a level below that of section 60. Tubes responding to tones of still higher frequency are supported at still lower levels, 64 and 66, the tubes of each group 24³ and 24⁴ being arranged concentrically with respect to the tubes of the other groups as indicated more particularly in Fig. 5 of the drawings.

It is in general preferable to employ four levels or groups of tubes arranged in the order of ascending frequency from the outer to the inner tubes, although obviously any number of levels may be used.

The tubes are preferably supported in each section as indicated in the cross sectional view in Fig. 7 by means of two plates or boards, as 60' and 60², having a layer of celotex, felt or the like, 60³ between them. A series of cylindrical sections 68, 70, and 72, preferably of glass, may be employed for supporting the next lower supports 62, 64 and 66, extending from the upper annular section to the next lower, the cylindrical supporting boards being concentrically arranged with respect to the outside casing, so as to add to the ornamental effect produced by the arrangement.

The cylindrical supporting boards may be of bakelite or other suitable composition, in place of glass, if desired, although glass is preferable for the reason that a glass cylinder on account of its thickness, see Fig. 7 does

not vibrate during the use of the apparatus. In order to assist in obtaining a compact structure, and to prevent undesired vibration, the next adjacent supports at the different levels are interconnected by means of a series of columns or stays 74, 76, and 78 which may be made of glass or bakelite to carry out the ornamental scheme of the device. By the use of the construction and arrangement of the tubes at a plurality of levels and concentrically arranged in the order of ascending frequencies, with the tubes for resonating high frequencies furthest from the sound generating means, in the manner shown, it has been found that a superior selectivity in resonating separate sound waves is obtained.

In the operation of the device above described, sound frequencies which are generated by the sound generating means 14 pass through the cone or horn 16 and are dispersed in the sounding box 10 being deflected by the tube board 22 and passing into the tubes 24 mounted thereon. The deflection of the sound vibrations by the tube board 22 causes or sets up an echo which accompanies the wave of which it is an echo and serves to clarify and reinforce the original sound wave or vibration. The sound waves which are amplified by and discharged through the tubes 24 pass downwardly through the cylindrical casing 30 to the surface of the water or liquid 40 in the container 42, the liquid being thereby set into vibration in unison with the resonating sound waves.

Impact or contact of the sound waves with the surface of the water or liquid 40 sets up another echo or reinforcement which further clarifies and reinforces the sound wave or vibration of which it is an echo, and accompanies the vibration of which it is an echo. The sound waves produced with the corresponding vibration of the liquid or water in the container 42 are transmitted or dispersed to the sloped sides 46 and 50 of the container, and leave the surface of the water at the point of greatest intensity of the vibration, namely, at the surface portion of the water where the water is the most shallow, the waves rolling up the sides of the container and discharging into the auditorium or chamber in which the device is suspended or used.

While the preferred arrangement of tubes is that shown in Figs. 5, 6 and 7, the modified arrangement of tubes at different levels illustrated in Figs. 8 and 9 may be used. In this form of arrangement the tubes of the groups 24¹, 24², 24³ and 24⁴ are arranged in tiers, similarly to the groups above described, but instead of being suspended from circular supports or annuli, are supported in a square arrangement of any desired number of groups or tiers, the square supports 22¹, 22², 22³ and 22⁴ being arranged symmetrically as shown. While with the circular

form of support the casing is preferably made of glass, in the square board arrangement a glass casing does not operate satisfactorily because of vibration and bakelite or some other suitable material is therefore used for the casing with this arrangement. In the square arrangement it is preferable to have the corners of the squares, which are preferably of wood, modified by removing a section as shown more particularly in Fig. 9, thereby avoiding undesired vibrations in the construction. Furthermore, in order to protect against the possibility of distortion occurring by reason of any crack between the boards forming this tube board, if wood is used, it is desirable to cover it with a coating of beeswax. This tube board, however, may be made of an aluminum die-casting in a single piece or made of other suitable material.

It is to be understood that the device which has been described may be made either in the form emitting vibrations in all directions or in a single direction. If it is desired to discharge the sound waves from the surface of the water in a unitary or single direction, the walls of the interior of the liquid container should be made perpendicular except at the side in the direction in which it is desired to discharge the sound waves, at which side the interior of the box or liquid container should be sloped at a suitable angle, preferably of about 45° or somewhat less with the horizontal. It will be understood in this connection that in the transmission of the sound or vibration frequencies from a liquid container, the sound seeks the path of least resistance, emanating from the point in the container where the water or liquid is the most shallow.

In the use of the device for ornamental purposes, the apparatus is preferably suspended by means of a series of chains as described. If desired, the device may be illuminated or used for illuminating purposes, in addition to serving for the transmission of sound, by embodying suitable lighting devices on the exterior portions of the liquid container or on the supporting member for the cylindrical casing surrounding the resonating tubes. It is to be understood also that the device may be suspended within a chandelier or other fixture designed to receive it, provided, however, that the chandelier or other fixture offers no obstruction or impediment to the discharge of sound waves from the surface of the water or interference with the vibration of the sounding box or tubes, as will be apparent to those skilled in the art.

It will be understood also that various changes or modifications may be made in the device above described without departing from the spirit or scope of the invention as defined in the following claims.

Having thus described the invention, what is claimed as new is:

1. A sound resonating and modulating device adapted particularly for ornamental use comprising a cylindrical casing, sound generating means connected to said casing, a plurality of tubes within said casing, a container for liquid positioned to receive sound waves from said tubes and means for emitting sound waves from the surface of the liquid without interference with the sound vibrations. 70
2. A sound resonating and modulating device adapted particularly for ornamental use comprising a glass cylindrical casing, a sound generating means connected to the said casing, a plurality of resonating tubes suspended within said casing, a container for liquid positioned below said tubes to receive sound waves therefrom and an angular outlet from said container for emitting sound waves at an angle not greater than about 45° with the horizontal. 80
3. A sound resonating and modulating device adapted particularly for ornamental use comprising sound generating means, a sounding box connected thereto in the form of a polygon in horizontal section, a tube board connected to the said sounding box, resonating tubes suspended from the said tube board, a cylindrical casing surrounding the said tubes, a container for liquid positioned below the said casing, means for directing sound vibrations from the said resonating tubes to the liquid in said container and means for emitting sound waves from the surface of the liquid without interference. 90
4. In a device of the kind described, a glass cylinder, a cylinder-supporting member having an opening communicating with the interior of the said cylinder, a series of resonating tubes suspended within said cylinder, a container for liquid suspended from the said cylinder-supporting member, sound generating means in communication with said tubes and means for suspending the said device in an auditorium or theater, so as to have the ornamental appearance of a chandelier. 100
5. A sound resonating and modulating device comprising a casing of non-resonating material in the form of a closed curve in section, a support for said casing having an opening communicating with the interior of said casing, a series of resonating tubes suspended within said casing, a container for liquid suspended from the said support in a position to receive sound vibrations emitted by the said resonating tubes, sound generating means in communication with said tubes and chain supporting means for interconnecting and suspending parts of the device and for suspending the said device from a ceiling or other suitable support so as to have the ornamental appearance of a chandelier. 110
6. In a device of the kind described, the

sub-combination comprising tube supporting means having sections arranged in tiers, resonating tubes connected in groups to the said sections, the said groups being symmetrically arranged with respect to each other. 120

7. In a device of the kind described, the sub-combination comprising tube supporting means having a series of supports arranged at different levels, a group of tubes connected to each support responding to frequencies of the same order, the group of tubes responding to the lowest frequencies being connected to the most elevated support and arranged symmetrically with respect thereto. 130

8. In a device of the kind described, the sub-combination comprising tube supporting means having annular sections arranged in tiers, resonating tubes connected in circular groups to the said annular sections, the said groups being symmetrically arranged with respect to each other. 140

9. In a device of the kind described, the sub-combination comprising tube supporting means having a series of annular supports arranged at different levels, a group of resonating tubes symmetrically arranged in a circle and connected to each support, the groups of tubes being arranged in the order of ascending frequencies from the outer lowest group of tubes to the inner tubes of highest pitch. 150

10. A sound resonating and modulating device having superior selectivity in the resonance of separate sound waves comprising in combination a glass cylindrical casing, a sounding box connected thereto, tube supporting means adapted to hold groups of tubes at different levels, resonating tubes suspended from the said tube supporting means and symmetrically arranged on the said tube supporting means, the group of tubes responding to the lowest frequencies being arranged on the outside, and those of the higher octaves being arranged progressively inwardly in the device, the tubes being furthermore arranged progressively at lower levels in their order of ascending frequencies. 160

11. In a sound resonating and modulating device, the subcombination comprising tube supporting means in which resonating tubes, adapted for the resonance of a wide range of frequencies, are mounted, so that tubes for the resonance of the higher frequencies are positioned further from the sound generating means than the tubes adapted for lower frequencies. 170

12. In a sound resonating and modulating device, the subcombination comprising tube supporting means in which resonating tubes are symmetrically mounted thereon so that the tubes of shorter length responsive to higher frequencies are positioned further from the sound generating means than the tubes adapted for lower frequencies. 180

13. In a sound resonating and modulating device, the subcombination comprising a sound generating means, and tube supporting means having a group of symmetrically arranged resonating tubes adapted for the resonance of sounds through a wide range of frequencies, the tubes being mounted at different levels so that those responsive to high frequencies are positioned further from the sound generating means than tubes adapted for the lower frequencies.
14. In a device of the kind described, in combination, a plurality of open-ended tubes arranged in groups at different levels, a casing surrounding the tubes, and sound generating means substantially in line with the tubes so as to project sound waves directly into the open ends of the tubes, the sound waves being resonated through the tubes and projected out of the opposite ends thereof.
15. In testimony whereof I hereunto affix my signature.

CHRISTIAN A. VOLF, JR.
